UNITED STATES PATENT OFFICE.

EDWARD P. DECKER, OF NEW YORK, N. Y.

DRIER.

Application filed November 17, 1927. Serial No. 233,814.

The invention relates to drying apparatus where wet or damp pulverulent or friable materials are freed of their moisture content. As an example of such materials may be cited peat and light chemical substances. With such materials it is desirable to avoid as much as possible, the further disintegration of the lumpy constituents and it is also desirable to remove the finer or dusty particles as they become loosened during the drying process.

My invention comprises means for accomplishing these results and consists of the combination with a trembling separator over which the material is made to pass, with means for applying the heat from heated gases to the material as it passes over the separator. The drying operation assists the separation of the finer particles and their consequent accumulation at the bottom of the layer of material. The invention therefore further comprises the combination with such heating and separating means of means for sifting out the finer materials after they have been so forced to the bottom, the specific means being a sifting screen, also of the vibrating and trembling character, acting in conjunction with the vibrating separator heater by being made a continuation thereof. As further heating and vibrating will separate still more fine material, my invention further comprises a tandem arrangement of the heating and vibrating separators and sifters, the number of these duplications that are to be used, being dependent in large measure on the quality of the raw material and the quality of the product that is desired to be obtained.

An embodiment of my invention will now be described with reference to the accompanying drawings in which

Figure 1 shows a longitudinal section, and Figure 2 shows a transverse section on the line 2—2 of Figure 1.

An inclined trough 1 has the material supplied to it at the upper end by any suitable means such as a chute or hopper 2. At 3 are shown electromagnetic vibrators which are mounted at intervals over the trough 1 and are adapted by their magnetic pulsations to give to the trough a trembling movement that will result in the movement of the finer particles to the bottom of the material layer and the coarser fragments to the top. The bottom of the trough has parts 4 that are made of impervious sheet metal and other

parts 5 of screening that form continuations of the non-pervious parts 4. Under the non-pervious parts 4 are heating chambers 6 to which hot gases are introduced by pipes 7 and from which the gases escape by pipes 8. The chambers 6 are preferably encased or protected from radiation by non-conducting coverings 9. Under the screening parts 5 are collecting hoppers 10 into which the fine material is deposited as it is shaken through the screens and from such hoppers the material may be removed in any desired manner as, for example, by screws 11. A final hopper and its screw 11 is adapted to receive and remove the unscreened material.

In operation, the moist or wet material, as for example peat in a proper degree of subdivision, is fed to the separator through hopper 2. The vibration of the trough 1 by the magnetic vibrators 3 causes the material to spread out over the bottom of the trough and slowly travel down the whole length of the trough until finally discharged into terminal hopper 12. The action of these trembler screens is in itself well-known; but as employed in the present combination, it is to be noted that the vibratory impulses given to the bottom of the trough 4 and the screens 5 impel the pulverulent material upward at a right angle to the direction of travel so that the material falls back upon the trough and screen at varying distances along the direction of travel. The coarser particles are impelled a greater distance than the finer particles so that they progress faster in the direction of travel and tend to collect their places in the upper layer, whereas the finer particles are not impelled so far and tend to accumulate in the lower layer. This impelling of the finer and coarser particles from the trough bottom and screen repeatedly separates the particles from contact with each other and exposes them to the drying effect of the radiant heat from the trough bottom and the absorption of moisture by the surrounding air to which the particles are thus more advantageously exposed. The material as it passes over the non-pervious portions 4 is heated by contact therewith. As it is thus dried, the finer particles are shaken to the bottom and lying next the hot plates 4 are further dried so that as the material passes off the plates 4 and onto the screens 5, the finer particles that have become sufficiently dried to be capable of being sifted

through the screen, are thus separated from the traveling layer of material and are collected in the hopper 10 and removed by screws 11. The material passing again over plates 4 will now be freed of the already dried finer particles and will be subject to a more efficient further drying and separating. In this way by successive dryings and removal of fines, the final product will be found to consist of only clean coarse material

10 I claim:

1. A drier comprising in combination, an inclined impervious drying support and an inclined screen forming a continuation of the support, means for vibrating said support and screen to impel the material vertically from the support and screen and cause it to gradually descend and pass the finer particles to the bottom, and means for applying heat to the support to dry the fines so that they will more easily pass through the screen.

2. A drier comprising in combination, an inclined impervious drying support and an inclined screen forming a continuation of the support, means for vibrating said support and screen to impel the material vertically from the support and screen and cause it to gradually descend and pass the finer particles to the bottom, means for collecting the fines below the screen, and means for applying heat to the support to dry the fines so that they will more easily pass through the screen.

3. A drier comprising in combination, an inclined impervious drying support and an inclined screen forming a continuation of the support, means for vibrating said support and screen to impel the material vertically from the support and screen and cause it to gradually descend and pass the finer particles to the bottom, and a heating chamber beneath the support for applying heat to the sup-

port to dry the fines so that they will more easily pass through the screen.

4. A drier comprising in combination, an inclined impervious drying support and an inclined screen forming a continuation of the support, means for vibrating said support and screen to impel the material vertically from the support and screen and cause it to gradually descend and pass the finer particles to the bottom, and a heating chamber with gas inlets and outlets beneath the support for applying heat to the support to dry the fines so that they will more easily pass through the screen.

5. A drier comprising in combination, an inclined impervious drying support and an inclined screen forming a continuation of the support, means for vibrating said support and screen to impel the material vertically from the support and screen and cause it to gradually descend and pass the finer particles to the bottom, and a heating chamber beneath the support for applying heat to the support to dry the fines so that they will more easily pass through the screen, said chamber having its bottom and sides protected from radiation by heat insulation.

6. A drier for pulverulent material comprising in combination, an inclined material support consisting of a plurality of impervious supports alternating with a plurality of screens, means for vibrating said support and screens in a direction at a right angle to their surface to impel the pulverulent material directly away from the said surface, receptacles under the screens for receiving the fines, and separate heating means under the supports whereby the material is subjected to a repeated heating and screening while being vibrated.

EDWARD P. DECKER.
